UNITED STATES PATENT OFFICE.

EDWARD R. JONES, OF BALTIMORE, MARYLAND.

SASH-LOCK.

1,175,525.

Specification of Letters Patent. Patented Mar. 14, 1916.

Application filed April 14, 1915. Serial No. 21,203.

To all whom it may concern:

Be it known that I, EDWARD R. JONES, a citizen of the United States, residing at Baltimore, in the State of Maryland, have 5 invented certain new and useful Improvements in Sash-Locks, of which the following is a specification.

This invention relates to improvements in sash locks and has particular reference to a 10 lock device for window sashes whereby to lock the sash in a fully closed position or lock it in a partially open position in such way as to prevent it from being further opened.

15 In illustrating the invention I have shown the improved device on one side of a lower window sash, but it is to be understood that preferably both sides of the sash are provided with the improvement and that both 20 the lower and upper sashes will be locked in the same manner but by separate lock devices. The lock device for both sides and for both sashes being of the same construction, I deem it sufficient to show only one 25 of them.

In the accompanying drawing, Figure 1, shows a front elevation of a window frame and the two sashes therein,—the outer casing board of the frame being removed to 30 show the improved lock for the lower sash. Fig. 2, illustrates in side elevation, that part of the lock device which is carried by the frame,—the sashes being removed. Fig. 3, shows an enlarged sectional detail through 35 one vertical edge of the sash to show the sash portion of the lock device in engagement with that part which is carried by the frame. Fig. 4, illustrates a portion of the sash edge with the sash lock in place 40 therein. Fig. 5 shows the frame guides in which the sashes slide,—the lower sash being removed to illustrate the covering plate to conceal and protect the lock devices in the frame, and Fig. 6, illustrates a cross- 45 sectional detail through the lower sash and frame,—the section being taken on the line 6—6 of Fig. 1.

Referring to the drawing, the numeral 7, 50 designates one vertical side of the frame box or casing on one side of which two vertical channels 8 and 9, are formed to serve as guides for the lower and upper sashes 10 and 11 respectively. Each sash has a recess or mortise in its vertical edge, in which 55 a metal case 13, fits. This metal case carries two pivoted pawls 14 and 15, respectively,—

the free end of the former being inclined upwardly while the free end of the latter is inclined downwardly. By referring to Fig. 3 of the drawing it will be seen that the 60 free ends of both pawls 14 and 15 project outwardly beyond the vertical side edge of the sash and are yieldingly held in such outwardly-projected position by means of the pressure of the ends of a spring plate 16. 65 The metal case 13, which is carried by the sash is provided with two spaced-apart laterally-projecting arms 17, which extend from the opposite vertical side walls of said case for a purpose presently to be described. 70

Adjacent to the vertical side edge of the sash I provide a vertical rod 18, which latter has its lower end supported in a bearing plate 19, carried in the present instance on the sill 20, and its upper end held in a 75 bracket plate 21, that projects from the casting 7. The vertical rod therefore is sustained so that it may be oscillated, and an arm 22, is provided on the rod so that one end of a rock bar 23, may engage said arm 80 while the other end of the bar may be operated by an arm 24, which projects at the outer side of the window casing. A pivot 25, sustains the rock bar between its ends so that by pushing arm 24, inwardly the rock 85 bar may be operated to turn rod 18, in one direction whereas upon pulling said arm outwardly the rock bar will be operated to turn said rod 18, in a reverse direction.

Vertical rod 18, is provided with two 90 rows of notches 26 and 27, respectively, each row being in a different vertical plane on the rod. The notches 26, are upwardly-inclined on the rod while the row of notches 27, are downwardly-inclined on said rod. 95 The upwardly-inclined notches 26, form stops to be engaged by the upwardly-inclined pawl 14, on the sash, while the downwardly-inclined notches 27, form stops for the engagement of the downwardly-inclined pawl 15, on the sash. By turning the rod 18, so that the row of notches 26, will have position at the side of the pawls, the pawl 14, will engage those notches and prevent raising of the sash, but lowering of 100 the sash can take place because notches 27, will be turned out of the path of pawl 15, which locks the window against downward movement.

In the case of sashes that have no balance 110 weights, I provide a coiled spring 28, on the rod, the lower end of which spring seats

on a collar 29, from which arm 22, projects, while the upper end of the spring seats under a loose collar 30, on the rod. This upper collar 30, forms a yielding support 5 for the arms 17, that project from the sash and the rod 18, extends vertically between said arms. In this way the sash is yieldingly sustained by the spring 28,—the collar 30, and arms 17, being interposed between the sash and spring. In order to conceal and also prevent tampering with the rod 18, I provide a plate 31, which I interpose between the sash and the rod and which is held in place by the guide strips 32, so 10 that when a sash is partly opened, access to the rod will be prevented.

From the foregoing explanation it will be understood that if it is desired to raise the lower sash sufficiently to aid ventilation, 20 the rod 18, may be turned so as to present the notches 26, to the side edge of the sash, as shown in Fig. 1, of the drawing, whereupon pawl 14, will engage one of said notches 26, and prevent further raising of 25 the sash. The sash may however be lowered without operating the rod 18. If it is desired to hold the sash from being drawn down the rod 18, will be turned so as to present notches 27, to the side edge of the sash, as shown in Fig. 3, whereupon the pawl 15, will engage one or another of said notches 27, and prevent downward movement of the sash. By providing vertical rods and locking devices at opposite edge 35 of each sash, and turning the rod at one side to present one row of notches for engagement and move the rod at the opposite side to present the other row of notches for engagement, the sash will be locked against movement in either direction.

Having described my invention what I claim is,—

1. The combination with a window frame, 45 of a sash slideable with respect to the frame; a pawl device on the sash; a bar at the side of the sash and having a row of notches therein with which the pawl may engage and means for rotating the bar to shift the row of notches with respect to the pawl.

2. The combination with a window frame, 50 of a sash slideable with respect to the frame; two pawl devices on the sash; a rotary bar at one side of the sash and having two rows of notches therein and means for rotating the bar to present a row of notches to one 55 pawl at a time.

3. The combination with a window frame, 60 of a sash slideable with respect to the frame; two pawl devices on the sash; a vertical bar adjacent to the sash and the pawls thereon,—said bar being rotatably mounted and having two vertical rows of notches in different planes and means for rotating the bar to present one row of vertical notches at a time for engagement by a pawl. 65

4. The combination with a window frame, 70 of a sash slideable with respect to the frame; an upwardly inclined pawl on the sash; a downwardly inclined pawl also on the sash; a vertical bar at the side of the pawls said bar having a row of upwardly-inclined notches and another row of downwardly-inclined notches and means for moving the bar to present one row of notches at a time for engagement by one of the pawls on the 75 sash.

5. The combination with a window frame, 80 of a sash; a metal case in the side edge of the sash; two pawls projecting from the metal case,—one in an upwardly-inclined direction and the other in a downwardly-inclined direction; means in the case for yieldingly pressing the pawls; a rotatable bar extending vertically at the side of the sash and said bar having one set of notches 85 to engage one of said pawls and another set of notches to engage the other of said pawls, and means for rotating the bar to move one set of notches into operative relation with one of said pawls and the other set of 90 notches out of operative relation with the other of said pawls.

In testimony whereof I affix my signature in presence of two witnesses.

EDWARD R. JONES.
